PIPE CADDY

Reuben G. Thoreen, 522 S. Broadway St., Stillwater, Minn., and Mather Garland, Rte. 1, Box 592, Excelsior, Minn.

Filed Mar. 13, 1964, Ser. No. 78,990

Term of patent 14 years

(Cl. D85—8)

FIG 1

FIG 2

FIG 3

FIG 4

FIG 5

FIGURE 1 is a front elevational view of a pipe caddy embodying our new design;

FIGURE 2 is a top plan view;

FIGURE 3 is a rear elevational view;

FIGURE 4 is an end elevational view looking from the right of FIGURE 1; and

FIGURE 5 is an end elevational view looking from the left of FIGURE 1.

We claim:

The ornamental design for a pipe caddy, as shown.
